UNITED STATES PATENT OFFICE.

EDMUND E. WERNER, OF CARROLL, NEBRASKA.

DESIGN FOR A TIRE.

Application filed June 16, 1927. Serial No. 22,460. Term of patent 14 years.

To all whom it may concern:

Be it known that I, EDMUND E. WERNER, a citizen of the United States of America, residing at Carroll, in the county of Wayne and State of Nebraska, have invented a new, original, and ornamental Design for a Tire, of which the following is a specification, reference being had to the accompanying drawing, forming a part hereof.

In the drawing:

Figure 1 is a plan view of a portion of a tire showing my design;
Fig. 2 is a side elevation of the same, and
Fig. 3 is a fragmentary transverse section on the line 3—3 of Fig. 1.

I claim:
The ornamental design for a tire, as shown.

EDMUND E. WERNER. [L. s.]
